US00D880148S

(12) **United States Design Patent** (10) Patent No.: **US D880,148 S**
(45) Date of Patent: ** Apr. 7, 2020

(54) **LANYARD**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Daniel J. Coster**, San Francisco, CA (US); **Danielle De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/594,996**

(22) Filed: **Feb. 24, 2017**

Related U.S. Application Data

(63) Continuation of application No. 29/518,892, filed on Feb. 27, 2015, now Pat. No. Des. 779,814, which is a continuation of application No. 29/453,543, filed on Apr. 30, 2013, now Pat. No. Des. 723,264, which is a continuation of application No. 29/431,562, filed on Sep. 8, 2012, now Pat. No. Des. 680,895.

(57) CLAIM

The ornamental design for a lanyard, as shown and described.

DESCRIPTION

FIG. 1 is a top front perspective view of a lanyard showing the claimed design;

FIG. 2 is a bottom rear perspective view thereof;

FIG. 3 is a top view thereof;

FIG. 4 is a side view thereof;

FIG. 5 is another side view thereof;

FIG. 6 is a front view thereof;

FIG. 7 is a rear view thereof; and,

FIG. 8 is an enlarged view of a portion of FIG. 1.

The broken lines in the figures show portions of the lanyard that form no part of the claimed design.
